UNITED STATES PATENT OFFICE.

WALTER S. MENDENHALL, OF NORWOOD, OHIO, ASSIGNOR TO THE SAMUEL C. TATUM COMPANY, OF CINCINNATI, OHIO.

PAPER-PERFORATOR.

SPECIFICATION forming part of Letters Patent No. 634,304, dated October 3, 1899.

Application filed October 27, 1898. Serial No. 694,664. (No model.)

To all whom it may concern:

Be it known that I, WALTER S. MENDENHALL, residing at Norwood, in the county of Hamilton and State of Ohio, have invented 5 certain new and useful Improvements in Paper-Perforators, of which the following is a specification.

The object of this invention is to provide a machine for punching simultaneously two or 10 more holes through a single or a series of sheets of paper at one operation.

Another object of my invention is to provide means for adjusting or changing the distance between the punches.

15 Another object of my invention is to provide a receptacle for the material punched out.

Another object of my invention is to provide suitable guides and gage devices for 20 properly presenting the paper to the action of the punches.

The features of my invention will be more fully set forth in the description of the accompanying drawings, making a part of this specification, in which—

25 Figure 1 is a perspective view of the punching-machine. Fig. 2 is a vertical section on line $\alpha\alpha$, Fig. 1. Fig. 3 is a modified form of the adjusting devices. Fig. 4 is a top plan view of a modification of my device.

30 A represents a bed-plate upon which is mounted the punching apparatus. B B' represent brackets, one of which is shown as rigidly attached to said bed-plate. The other is longitudinally adjustable on the bed-plate.

35 C represents the punching-levers. They are connected to their respective brackets by center pivots a .

b represents a spring, preferably of grasshopper form, bearing against the bracket- 40 punching arms for holding the punch-levers normally open.

D D' represent the punches secured to the front ends of each of the respective brackets. These punches are shown as surrounded by a 45 yielding sleeve. These punches are made of a size just to fit and enter the orifices c of the punching-lever with which they coact in forming the holes in the paper. It is very desirable to adjust the distance between these two 50 punches so that the holes may be formed any

desired distance apart. To accomplish this, I provide a guide-rod E. Bracket B' is adjusted longitudinally on this guide-rod, as will be hereinafter explained.

F represents cam-levers, each of which is 55 pivoted to the respective punch-levers C. The arms C are bifurcated, and the levers F are pivoted between the jaws thereof.

G represents a coupling guide-rod, one end of which is affixed to the eye of one of the 60 arms F, and the eye of the opposite arm F serves as a guide-rest.

The bracket B' and its contained arm are longitudinally adjustable upon the rods E and G, thereby allowing the distance between said 65 punches to be regulated.

H represents a set-screw for securing bracket B' to any adjusted position.

In the modification shown in Fig. 3 the guide-rod E is swiveled in the bracket B, so 70 as to journal therein. Rod E is screw-threaded along its central portion, which threads engage in female threads formed in the bracket B'. Said rod is shown as journaling in hanger I, through which it protrudes. K represents 75 a crank, which is affixed to the end of said rod. By turning said crank the rod is revolved and the thread moves the bracket longitudinally along the base A. The advantage of employing the screw-threaded rod is that 80 the punches need not be provided with additional means for securing the bracket in its adjusted position.

The use of the two guide-rods prevents any but longitudinal motion, and the upper guide- 85 rod G connects the two arms together and serves as a handle to the levers.

J J represent a series of guides affixed to the bed-plate in front of the punches. They are shown as slightly higher than the top of 90 the punch, so as to properly guide the paper. The front end of the punch-levers is rounded off, as shown at d , so as to assist in directing the paper between the two members of the punches.

L represents a gage sliding in a gain M, its upright arm extending up outside of the bracket B. It forms a slide-guide for directing the paper into the punches, so as to punch successive sheets in the same relative posi- 100

tions. N represents a set-screw for securing said gage to any adjusted position. As constructed, the ears O of the brackets B B' project up vertically and serve as a stop, against which the paper rests during the perforation.

In Fig. 4 I have shown a modification which only differs from the device of Fig. 1 in that the screw shown as attaching the bracket B to the base in Fig. 1 are omitted, and the other 10 end of the rod E is supported in a hanger I'. It is obvious that either one or both brackets may be adjusted on said rod to secure the desired mutual adjustability without departing from my invention. For convenience of attachment and detachment the end of the rod is secured in the hanger I' by a thumb-screw. II' represents the adjusting-screw on bracket B'. In practice the left-hand bracket is normally fixed relative to the coacting bracket; 20 but they may be mutually adjusted, if desired, and this form has certain conveniences—to wit, the facility with which it can be put together or taken apart, which renders it very useful.

25 P represents a cap having a stem e screw-threaded into the front end of the arm C and vertically over the punch. It is provided with an orifice or passage registering with the orifice c, so that the cuttings of the paper will be 30 passed up into the said receptacle. R represents a cover for said cap. This cap is shown as detachable for convenience of construction. The essential idea of this feature is the employment of a receptacle for the cuttings, 35 properly located relative to the female punch member, which receptacle may or may not be provided with a cover without departing from the invention.

Having described my invention, I claim—
40 1. In a paper-perforator, the combination of a pair of brackets mounted upon a longitudinal guide-rod, one of said brackets being adjustable thereon, pivotally-connected male

and female members carried by each bracket, levers for operating said punches, a rod connecting said levers and one of said levers being adapted to slide thereon, substantially as specified.

2. In a paper-perforator the combination with a suitable base, a pair of brackets each 50 provided with pivotally-connected male and female members, operating-levers for said punches, a longitudinal guide formed on said base, one of said brackets being adjustable thereon, and means connecting said levers 55 adapted to simultaneously operate the same, substantially as specified.

3. In a paper-perforator the combination with a supporting-base of a pair of brackets mounted thereon, each provided with pivotally-connected male and female members, operating-levers therefor, a longitudinal guide formed on said base, a connecting-rod passing through the lever members, one of said brackets being adjustable on said guide and means 65 for securing said bracket in position, substantially as specified.

4. In a paper-perforator, the combination of a pair of brackets mounted upon a suitable base, a longitudinal guide-rod supported by 70 said brackets and mounted on said base, one of said brackets being longitudinally adjustable thereon, means for securing said bracket in its adjustment, pivotally-connected male and female members mounted upon each 75 bracket, levers for operating the same, a rod connecting the said levers, and paper-guide supports mounted in front of said brackets, substantially as specified.

In testimony whereof I have hereunto set 80 my hand.

WALTER S. MENDENHALL.
